UNITED STATES PATENT OFFICE.

NOAH E. LUCAS, OF NORWICH, CONNECTICUT.

BOBBIN.

Application filed September 14, 1925. Serial No. 56,195.

My invention relates to the class of devices used in spinning, and upon which material, as roving is wound and from which it is unwound in the spinning operation, and an object of my invention, among others, is the production of a bobbin from which the waste mass that is usually left on the bobbin after the principal part of the mass has been taken off may be readily removed, and without the use of devices other than the hand.

One form of bobbin embodying my invention and in the construction and use of which the objects herein set out, as well as others, may be attained, is illustrated in the accompanying drawings, in which—

Figure 1 is a view in side elevation of a bobbin embodying my invention.

Figure 2 is an end view of the same.

20 In the operation of spinning a mass of material in the form of a strand and composed of cotton or other fiber, and that is commonly termed "roving" is wound upon a bobbin in a more or less even manner, and as a further step in the spinning operation this strand is unwound from the mass in a manner that will be readily understood by those skilled in the art. It generally happens, however, that this mass is not entirely removed from the bobbin in the spinning operation, and it, therefore, becomes necessary to remove this mass, that may be termed "waste" before the bobbin can be again put into use.

35 It has been a common practice heretofore to remove this waste mass from the bobbins by the use of a hook or knife, but this practice results in a mutilation of the bobbin that soon becomes unfit for use. Bobbin cleaning machines are also employed to a limited extent, but these are unsatisfactory.

40 My invention provides means whereby the bobbin may be readily cleaned of a waste mass by the use of the hands only, the use of hooks, knives, or other devices that will mutilate the bobbin being avoided, my improved bobbin, as illustrated in the drawings herein, comprising a body 5 that may be formed from any suitable material, as wood, and in the form commonly employed in devices of this class. The outer surface of this body is highly finished, as by polishing, or by being treated with a coating of varnish, shellac, or other substance that will provide a smooth glossy surface.

45 In order that the waste material may be

readily removed from the bobbin I provide a groove or grooves that extend in a spiral direction along the body of the bobbin, these grooves having means for exerting a slight 60 frictional hold upon the mass to resist, to a slight degree, turning movement of the bobbin within the mass. This causes the mass to be stretched sufficiently to loosen it, and if, at the same time that the force is 65 applied to turn the mass on the bobbin, another force be exerted to slide the mass toward the end of the bobbin, it will be found that the mass may be readily slid off such end of the bobbin.

70 This operation may be readily effected by grasping the mass with one hand and the larger end of the bobbin with the other hand, the latter being employed to turn the bobbin within the mass, and at the same 75 time to withdraw the bobbin from the mass. The grooves may be inclined to the right or to the left, and the direction of turning movement imparted to the bobbin in the operation of removing the mass will depend 80 upon the direction in which the groove or grooves extend or are inclined. If the groove or grooves incline to the left, as shown in the drawings, the bobbin should be turned to the left, but if the groove or 85 grooves incline or run to the right, then the bobbin should be turned to the right in the operation of removing the mass of waste material therefrom.

90 In the form of the device illustrated herein a groove 6 is formed extending in a spiral direction lengthwise of the bobbin and this groove is formed with a shoulder 7 along one edge, said groove tapering gradually 95 from said shoulder to the outer surface of the body and the shoulder is located on that side of the groove indicated by the direction in which the groove extends. That is, as illustrated herein the groove inclines to the left and the shoulder is, therefore, on the left hand side of the groove, but if the groove be inclined to the right, then the shoulder should be located on the right side of the groove. This description with respect to the grooves refers to such groove on 100 that side of the bobbin next to the observer in Figure 1 at the bottom thereof.

105 The bobbin is also provided with a groove 8 inclined in a spiral direction, as above described, this groove, however, being of substantially even depth from side to side and it is provided with a filling 9, of felt or

other material that will exert a slight frictional hold upon the mass deposited upon the bobbin. This groove is comparatively narrow, and the filling 9 is substantially flush with the outer surface of the bobbin, that is, it projects beyond such outer surface just enough to exert a slight frictional hold upon the mass of material upon the bobbin.

- 10 While I have illustrated my invention herein as embodying a bobbin with both forms of the groove herein above described I contemplate as within the spirit and intent of my invention a bobbin that may be 15 provided with either form alone of groove in such numbers as may be desired, or with both forms, or even with other arrangements of spiral grooves that will accomplish the same purpose.
- 20 A further purpose in providing the groove arranged as hereinbefore described is to facilitate the winding of the roving upon the bobbin, as such roving will adhere closer and tighter to the bobbin during the beginning 25 of the winding operation of such roving upon the bobbin, and during subsequent handling of the bobbin with the roving thereon the latter is prevented from sliding off from the end or nose of the bobbin.
- 30 It will be understood that the felt projects but a very slight distance beyond the surface of the bobbin, the showing in the figures of the drawing being somewhat exaggerated in order to bring out this feature.
- 35 In accordance with the provisions of the patent statutes I have described the principles of operation of my invention, together with the device which I now consider to represent the best embodiment thereof; but I 40 desire to have it understood that the device shown is only illustrative and that the invention may be carried out by other means and

applied to uses other than those above set out.

I claim—

45 1. A bobbin having a groove extending in a spiral direction lengthwise along the side thereof and of a pitch to aid in the removal of material therefrom in a mass on application of a relative turning movement to the 50 mass and bobbin, said groove having a single shoulder located at one side thereof, and means for supporting the bobbin.

2. A bobbin having a groove extending in a spiral direction lengthwise along the side 55 and partially around the bobbin, said groove having a single shoulder located at one side thereof, and means for supporting the bobbin.

60 3. A bobbin having a smooth polished surface with a groove therein extending lengthwise thereof, and a filling comprising material having an affinity for matter wound upon the bobbin, said filling being located in said groove with the outer surface of the 65 filling substantially flush with the outer surface of the bobbin.

4. A bobbin having a smooth polished surface with a groove therein extending spirally lengthwise thereof, and a filling comprising material having an affinity for matter wound upon the bobbin, said filling being located in said groove with the outer surface of the filling substantially flush with the outer surface of the bobbin.

75 5. A bobbin having a groove extending in a spiral direction along the side and lengthwise thereof, said groove commencing near the bottom of the bobbin and terminating substantially at the top and extending not more than once around the bobbin, said groove also having a single shoulder located at one side thereof.

NOAH E. LUCAS.
